UNITED STATES PATENT OFFICE.

ALFRED HEALD, OF PHILADELPHIA, PENNSYLVANIA, ASSIGNOR TO McCAL-
LUM, CREASE & SLOAN, OF SAME PLACE.

DESIGN FOR CARPETS.

Specification forming part of Design No. 6,355, dated January 21, 1873.

To all whom it may concern:

Be it known that I, ALFRED HEALD, of Philadelphia, Pennsylvania, have invented a Design for a Carpet-Pattern, of which the following is a specification:

The figure in the accompanying drawing represents sufficient of a carpet-pattern to illustrate my design, the principal features of which are the members A, B, and C. Each member A consists of a central cruciform ornament, *a*, and two ribbons, *b*, folded as shown, so as to present the appearance of four arms radiating from a common center. The members B have small central ornaments *d* and rectangular borders *e*, interrupted at opposite points by square figures *f*, joining each other

at the corners and crossed by diagonal ribs *g* which connect the members B and C. The members C are diamond-shaped, and have the interior ornamentation shown.

Irrespective of the colors employed, I claim—

The design for a carpet-pattern, substantially as described, and as represented in and by the accompanying drawing.

In testimony whereof I have signed my name to this specification in the presence of two subscribing witnesses.

ALFRED HEALD.
